[57] CLAIM

The ornamental design for a chair-mounted mouse pad assembly, as shown and described.

DESCRIPTION

FIG. 1 is a top perspective view of a chair-mounted mouse pad assembly showing our new design, the broken line drawing of a portion of a chair is for illustrative purposes only and forms no part of the claimed design;

FIG. 2 is a right side view thereof;

FIG. 3 is a left side view thereof;

FIG. 4 is a front view thereof;

FIG. 5 is a rear view thereof;

FIG. 6 is a top view thereof; and,

FIG. 7 is a bottom view thereof.

The broken lines around the top edge of the smaller cushion in FIGS. 1, 2, 3, and 5 and around the bottom edge of the smaller cushion in FIG. 7 represent stitching which are a part of the claimed design.
